ANDREAS GUSTAV WACKENREUTER, OF CHICAGO, ILLINOIS

PROCESS OF TREATING TANNING SOLUTIONS

Application filed April 30, 1928. Serial No. 274,100.

My invention relates to improvements in processes of treating tanning solutions, and it consists in the steps hereinafter set forth.

An object of my invention is to provide a process of treating tanning solutions which results in the removing of the resinous substances and other objectionable matter in the shape of red tannins, fiber, and other solids.

A further object is to provide a process of treating tanning solutions wherein the removal of the objectionable solids enables the solution to be concentrated when prepared for marketing and this concentrated form of the tanning solutions may be dissolved freely, thus being relieved of the objectionable solids.

A further object of my invention is to provide a process of treating tanning solutions for removing objectionable solids, together with mold and other fungi, which form in the solutions after hides have been subjected to the solutions.

A further object is to provide a process of treating tanning solutions whereby the removal of the objectionable solids will permit a freer absorption or penetration of the solutions in the hides, which gives the leather or hides a stronger fiber and makes the hides thicker.

Other objects and advantages will appear in the following specification, and the novel features of the invention will be particularly pointed out in the appended claims.

My invention is illustrated in the accompanying drawings, forming part of this application, in which

Figure 1 is a diagrammatic view of a centrifugal apparatus,

Figure 2 is a diagrammatic view of a condensing chamber,

Figure 3 is a diagrammatic view of a dissolving chamber, and

Figure 4 is a diagrammatic view of a vat.

My improved process of treating tanning solutions is carried out substantially in five stages; that is to say, in the first step a new or unused solution is treated to remove objectionable solids therefrom; the second step is the condensing of the tanning solution; the third step is the dissolving of the condensed tanning solution and preparing it for the sub-

jection of hides; the fourth step is the subjection of hides in the dissolved tanning solution, and the fifth step is the treating of the used tanning solution for removing other objectionable solids.

There are numerous kinds of tanning solutions. By the various kinds I mean solutions extracted from barks, beans, roots, shrubs, nuts, or wood. For illustration let us assume that quebracho wood is used for forming a tanning solution. This tanning solution is formed by first grinding or chipping the quebracho wood into fine bits. These fine bits of quebracho wood are then subjected to boiling water. The chips of the wood are boiled for a sufficient time to extract the tannin from the wood. The result is a solution consisting of from 5 to 20% tannin, non-tannins, and impurities in the shape of insoluble resinous matter, together with 80 to 95% water. This formation of the tanning solution is not a part of my invention.

In carrying out my invention, I make use of a centrifuge 1 having an inlet 2 provided with a feed pipe 3 extending from a receptacle 4 and communicating with the inlet. The inlet 2 communicates with a chamber 5 having an inner wall 6. The chamber 5 is provided with an outlet 7 which communicates with a delivering member 8. The member 8 is provided with an outlet spout 9 for a purpose hereinafter described. The new tanning solution, after it has been allowed to cool to normal temperature, is disposed in the receptacle 4 which is positioned above the centrifuge or bowl 1. The solution passes by gravity through the feed pipe 3 and into the chamber 5 through the inlet 2. The bowl 1 is rotated by a drive pulley 10 which is operatively connected to the bowl 1 through a driven pulley 11 and a belt 12. The bowl 1 is rotated at from fifteen thousand to forty thousand revolutions per minute. This revolution of the bowl 1 imparts a revolving motion to the solution as the solution enters the chamber 5. The centrifugal force of the solution is from twelve thousand to fifteen thousand times gravity and under pressure of approximately six hundred to one thousand pounds per

100

square inch. The new tanning solution may be passed through the bowl 1 and the objectionable solids removed therefrom at any temperature from 65° F. to 200° F., if so desired.

5 During the centrifugal motion of the solution, the lighter substances, such as the liquid portion of the solution, will retain the innermost portion of the body of the solution as it passes through the chamber, and 10 the solids, such as red tannins, fiber, and other solids, will be forced against the inner wall 6 of the chamber. The continued movement of the solution into the chamber 5 forces the liquid portion of the solution, 15 which has been treated, through the outlet 7 and into the delivering chamber 8, where the solution is guided through the spout into a container 13. Therefore, as the solution 20 passes from the receptacle 4 through the feed pipe 3, the inlet 2, and the chamber 5, the centrifugal motion imparted to the solution in the chamber 5 will force the solids contained in the solution outwardly where 25 they will be packed against the inner wall 6 of the chamber and allow the liquor portion of the solution to pass outwardly through the outlet 7, the member 8, the spout 9, and into the container 13. The 30 solution received in the container 13 is freed from the objectionable solids and these objectionable solids, which are in the form of red tannins, fibers, and other solid matters, are in a plastic form upon the inner wall 6. 35 This matter, which is formed of the objectionable solids, may be removed from the chamber 5 in any desired manner.

40 The next step of the process is the concentrating of the liquid or solution taken from the container 13. The liquid taken from the container 13 is disposed in a concentrating chamber 14 which is heated by any suitable heating means 15. The solution is heated within the concentrating 45 chamber until it becomes a compact form such as semi-paste, paste, or a solid. The tanning solution may be retained in this stage of concentration until it is to be made ready for the subjection of hides. While 50 the solution is in the concentrated stage, it is reduced from 80 to 95% in quantity.

55 The third stage of the process is the placing of the concentrated solution in a dissolving chamber 16 with water. The mixture will consist of from 5 to 20% concentrated solution and from 80 to 95% water. This mixture can be diluted with water at any desired temperature.

60 The solution is now ready for the hides to be submerged therein. In Figure 4 I have shown a diagrammatic view of a vat 17. The solution from the dissolving chamber 16 is then disposed in the vat 17, covering the hides which are to be treated by the solution. The 65 solution which was taken from the dissolv-

ing chamber 16 is kept in contact with the hides in the vats 17 for the desired length of time, which is about fifteen days.

70 The next stage of the process is the taking of the solution from the hides in the vat 17 and placing the solution in the receptacle 4. In this step of the process the used solution is reconditioned so that it may be again used for tanning hides. The use of the tanning solution, which is commonly termed as tan liquor, and its contact with the hides causes 75 not only the formation of lactic acid producing bacilli, which is very desirable, but also causes the formation of mold and other fungi, which are not only harmful to the 80 production of good leather, but also destroy a considerable percentage of tannin.

85 The used solution which is placed in the receptacle 4 passes by gravity through the feed pipe 3 and through the inlet 2 into the chamber 5. The chamber 5 is rotated at from fifteen thousand to forty thousand revolutions per minute. The centrifugal force imparted to the used solution which passes into the chamber 5 forces the objectionable solids which consist of mold and other fungi outwardly into engagement with the inner wall 6, where the solids will be impacted and held as the liquid portion passes outwardly through the outlet 7, the member 8, through 90 the spout 9, and into the container 13. The application of centrifugal force to the used tanning solution, while permitting the lactic acid forming bacilli to be retained in the solution, separates and eliminates the mold 95 and other harmful fungi. This reconditioning of the solution permits a freer multiplication of the lactic bacilli, resulting in a very much improved tan liquor or solution which penetrates the hide more quickly, plumps 100 it better, and gives the leather a much stronger fiber. Furthermore, the centrifugal action imparted to the solution eliminates all insoluble substances and substances which 105 are not leather producing.

110 The second and third stages, which are the condensing and dissolving stages, may be eliminated and the solution may be taken from the first stage and used in the fourth stage; i. e., in connection with the hides in the vat 17. The purpose of the stage two is to reduce the solution into compact form so that it may be readily handled and stowed away until ready for use. Furthermore, the 115 solution in the condensed form may be used more readily in commerce when the solution is prepared in one place and to be used in another.

120 The purpose of the third stage is to dissolve the condensed form of the solution and prepare it for actual use in connection with hides. As stated heretofore, the condensed form of the solution may be readily and perfectly dissolved due to the previous remov- 130

ing of the objectionable solids, which, when condensed, tend to prevent the dissolving.

I claim:

- 5 1. The herein described steps in a process of treating a tanning solution which consists in submitting the solution to the selective action of hides, separating the hides from the solution, removing solids from the solution, and concentrating it.
- 10 2. The herein described steps in a process of treating a tanning solution which consists in submitting the solution to the selective action of hides, separating the hides from the solution, centrifugating the solution to remove the solids, and heating the solution to concentrate it.

Signed at Chicago, in the county of Cook and State of Illinois, this 6th day of April, A. D. 1928.
